CABLE SUPPORT

John J. Taylor, Wadsworth, Ohio, assignor to The Ohio Brass Company, Mansfield, Ohio, a corporation of Ohio

Application May 31, 1935, Serial No. 24,315

8 Claims. (Cl. 248—63)

This invention relates to conductor supports and more particularly to supports for comparatively light electrical transmission lines, and has for one of its objects the provision of a support which may be used for conductors of various sizes and which will be of fairly simple and cheap construction, easy to install and efficient in operation.

Other objects and advantages will appear from the following description.

The invention is exemplified by the combination and arrangement of parts shown in the accompanying drawing and described in the following specification, and it is more particularly pointed out in the appended claims.

In the drawing:

Fig. 1 is a top plan view of one embodiment of the present invention.

Fig. 2 is an elevation of the conductor support or clamp shown in Fig. 1.

Fig. 3 is a section on line 3—3 of Fig. 2.

In the embodiment of the invention shown in the drawing, a body or seat member 10 is provided with a channel shaped seat 11 for receiving the conductor. The seat member 10 is curved downwardly at its ends to avoid an abrupt shoulder at the point where the conductor leaves the seat. A reinforcing rib 12 extends longitudinally of the seat member to provide ample strength without undue weight. Projecting laterally at each side of the seat member is a wing or flange 13, the flanges being perforated to receive a supporting U-bolt 14.

Disposed above the seat member is a keeper piece 15, one side of which is provided with a bearing face 16 having a longitudinal groove therein, the bearing face being curved in the direction of the length of the cable to conform approximately to the curvature of the seat in the body member 10. The keeper piece 15 is provided with laterally extending ears 17 which are also perforated to receive the U-bolt 14. At the opposite side of the keeper piece 15 from the seat 16 is a second seat 18 having a longitudinally extending groove formed upon a shorter radius of curvature than the grooved seat 16. The seat 18 is curved in a direction longitudinal of the cable in a reverse direction from the curvature of the seat 16 so that when the keeper piece is turned over to bring the seat 18 adjacent the cable, the longitudinal curvature will conform to the curvature of the seat 11. The portion of the keeper piece between the wing 17 and the seat 18 is made deeper than the portion between the seat 16 and the wings so that when the keeper

piece is reversed from the position shown in Fig. 3, the seat 18 will be closer to the seat 11 than the position of the seat 16 shown in the drawing. It will be readily apparent that the keeper piece in the position shown in the drawing will accommodate conductors of diameters ranging from that indicated by the smaller of the two broken line circles in Fig. 3 to that indicated by the larger of the two circles. For cables of smaller diameter than that shown by the smaller of the two broken line circles, the keeper piece is reversed and the seat 18 is used for engaging conductors of smaller size.

It will be noted from Fig. 3 of the drawing that when the cable is clamped in the support, the flat 15 faces of the lower nuts 19 engage the lateral faces of the seat member 10, thus locking the nuts 19 against rotation while the upper nuts 20 have sufficient clearance for the outermost portions of the nuts to pass the keeper piece 15. This is true of the upper nuts for both positions of the keeper piece 15.

In installing the device, the nuts 20 are backed off toward the bight in the U-bolt 14 and the cable is placed in position against the seat in the keeper piece 15. The seat member 10 is then placed in position and the nuts 19 threaded onto the legs of the U-bolt a sufficient distance to insure ample engagement between the nuts and the bolt. The nuts 19 are threaded onto their respective legs to corresponding positions so that the wings 13 on the seat member 10 may be lowered into engagement with the nuts and both nuts will operate to support the seat. The keeper piece is then lowered into contact with the cable and the nuts 20 threaded downwardly to clamp the keeper piece firmly against the cable. The nuts 20 may be provided with lock washers 21 if desired, but it will be apparent that it is not so important to lock the nuts since the weight 40 of the cable will hold the seat piece 10 upon the nuts 19 and retain the faces of the seat piece 10 against the faces of the nuts 19 so that it is impossible for the nuts 19 to become unscrewed from the U-bolt so as to drop the cable.

I claim:

1. A cable support comprising a cable seat, a bolt for supporting said seat, a nut for holding said seat on said bolt, said seat and nut having engaging portions for preventing rotation of said nut, said portions being relatively movable longitudinally of said bolt out of registration with each other while said seat is assembled on said bolt and while the nut engaging portion on said seat remains at a fixed distance from the axis of

- said bolt, said engaging portions being held in cooperative relation by gravity when said support is in operative position.
2. A conductor support comprising a seat member, a bolt for supporting said seat member, a nut threaded on said bolt, said nut engaging the lower face of said seat member, a projection on said seat member arranged to engage the lateral face of said nut to prevent rotation of said nut when said nut is in engagement with said lower face for supporting said seat member, said seat member being movable longitudinally of said bolt to a position in which said projection is out of registration with said nut but at the same distance from the axis of said bolt as it was while said nut was in engagement with said lower face, said lower face being held against said nut by the weight of the cable in said seat member.
3. A cable support comprising a pair of gripping members for engaging the cable, a bolt extending through said gripping members, a pair of nuts engaging said bolt for clamping said gripping members against said cable, means for supporting said bolt in an upright position to support said cable, the lower one of said gripping members having a stop for engaging the lateral face of the lower one of said nuts to prevent said lower nut from rotation, said lower gripping member being movable on said bolt to a position in which said stop is out of engagement with said lower nut to permit rotation of said lower nut on said bolt, said stop being held in cooperative relation with said nut by the gripping action of said nuts and by the weight of said cable on the lower one of said gripping members.
4. A conductor support comprising a seat member and a keeper piece each having a pair of perforations therethrough, a pair of bolts each extending through one of the perforations in said seat member and keeper piece, a pair of nuts on each of said bolts for pressing said seat member and keeper piece together to grip the cable therebetween, means for supporting said bolts with the keeper piece above the seat member, said seat member having means for cooperating with the lower one of each of said pair of nuts to lock said nuts against rotation, said seat member being movable to a position to permit rotation of the lower nuts of each pair and into operative position in which said nuts are locked against rotation, the upper nuts being arranged to press said keeper piece and the cable held by said support downwardly upon said seat to grip said cable and to hold said seat in the position in which the lower nuts are locked against rotation.
5. A cable support comprising an elongated seat member having the ends thereof curved downwardly and having a longitudinally extending groove in the upper face thereof forming a cable seat, a keeper piece for retaining the cable in said seat, said keeper piece having longitudinally reversely curved grooves in the opposite faces thereof, the curvature of the lowermost one of said grooves conforming to the curvature of the seat in said seat member irrespective of which side of said keeper piece is down, said grooves being (transversely curved) upon different radii to accommodate cables of different diameters said seat member and keeper piece each having laterally extending lugs thereon provided with registering perforations, and threaded members extending through said lugs for clamping said keeper piece against the cable in the seat in said seat member.
6. A conductor support comprising a pair of clamping members for the conductor having registering openings therein, a U-bolt each arm of which extends through one pair of registering openings in said clamping members, spaced nuts on each of the arms of said U-bolt for holding said clamping members together, abutments on the outer face of the outermost clamping member for engaging the endmost nuts respectively to prevent rotation thereof, said abutment members being held in operative engagement with said nuts when the innermost nuts on said arms are in position to press said clamping members together, said innermost nuts being retractable to permit said clamping members to be moved inwardly to free said abutment members from engagement with the outermost nuts.
7. A conductor support comprising a U-bolt, a pair of clamping members having registering openings engaging the arms of said U-bolt respectively, spaced nuts on each of said arms for holding said clamping members upon a cable extending therebetween, means on the outermost clamping member for engaging the outermost nuts on said arms to prevent said nuts from rotation, said means being held in engagement with said nuts by the weight of the conductor on said clamping member and by the innermost nuts on said arm when said innermost nuts are in clamping position, said clamping members being movable inwardly when said innermost nuts are retracted to free the outermost nuts from said engaging means.
8. In combination an elongated seat member having a longitudinally extending groove in the upper face thereof forming a cable seat, the ends of said cable seat being curved downwardly, a keeper piece for retaining the cable in said seat, said keeper piece having a groove therein registering with the groove in said seat member, said seat member and keeper piece each having laterally extending lugs thereon provided with registering perforations, a U-bolt having threaded legs extending through the perforations in said lugs, nuts threaded on said legs respectively for engaging the lugs on said keeper piece, and additional nuts threaded on said legs for engaging the lugs on said seat member, said nuts cooperating with said threaded legs for clamping a cable between said keeper piece and seat member, and means for locking the nuts engaging said seat member to prevent release of said cable.

JOHN J. TAYLOR.
